UNITED STATES PATENT OFFICE

FULVIO CALVANI, OF NEWARK, NEW JERSEY

SAXOPHONE

Application filed October 3, 1931. Serial No. 566,746.

The present invention comprehends a number of readily distinguishable and appreciable refinements and structural improvements embodied in the key operated mechanism, valved vents, and spring assembly means on a saxophone. My principal object is to improve generally upon prior patented and marketed musical instruments by simplifying the now intricate assembly by omitting certain troublesome valves and keys, and accomplishing new results without materially changing or interfering with the present day method or system of fingering.

By way of introduction, attention is first invited to the fact that one of the five improvements of this application is related to and recognized as an advanced improvement upon the invention covered in application Serial No. 453,280, filed by me under date of May 17, 1930, and allowed April 29, 1931.

In the aforesaid pending application, the principal change in construction and mechanism was predicated upon a novel method and means for operation of the C-sharp and D-natural valves in the low register of the instrument.

Admittedly, it is a matter of common knowledge to persons skilled in the art to which the invention relates that on the standard saxophone the C-sharp valve (in the low register) is normally closed, while the adjacent D-natural valve is normally open. Consequently, in either ascending or descending the chromatic scale, and encountering the key system in the low register, it is essential to resort to awkward and uncertain and sluggish fingering in producing the tones C-natural and C-sharp respectively.

As a matter of fact, in descending the chromatic scale, it is necessary under the present day arrangement to simultaneously depress the C-sharp and C-natural keys in order to close the D-natural valve, and to open the C-sharp valve in unison to produce the tone C-sharp. Obviously, this necessitates depressing the little fingers of both hands in unison and as these fingers are comparatively weak and the leverage system resistive in action, unusual skill and strength is required for smooth performance.

Fundamentally, what was accomplished in the aforesaid invention and what is also accomplished in the present invention is the provision of a mechanism and key control system which permits the aforesaid objection to be better overcome. The gist of the new idea is found in a unique arrangement of parts which permits both the C-sharp and D-natural pads or valves to remain normally unseated, said D-natural valve being separately and remotely controlled from the customarily or usual C-sharp key by the little finger of the left hand, and both valves being simultaneously closed or seated by the little finger of the right hand from the ordinary C-natural key.

Consequently, the little fingers of both of said hands may now be used quickly and successively as well as independently of each other for more rapid and precise manipulation. Incidentally, I shall not attempt to set forth commercially the very numerous advantages in tone control and intonation accomplished by the improvements of this application, but shall restrict the description and claims primarily to the revised and improved mechanical mechanism for structurally distinguishing my saxophone from similar ones.

The mechanism employed in the aforesaid pending case is decidedly improved upon in the present application and the details for accomplishing this result will be hereinafter specified.

A second feature of the present invention is predicated upon a supplemental device, in the nature of an attachment, for optional use mounted on the upper portion of the tubing and co-operating with the D-sharp valve and C-natural valve in the upper register for permitting said valves to be alternately operated from the index and second finger of the left hand, with a portion of said attachment co-operating with a novel duplex valve in a manner to lower the tone emitted from said C-sharp vent and to permit the practical playing of a trill or any regular passage from C to D-natural.

As implied, this particular attachment embodies a new key to be depressed by said index finger inasmuch as said D-sharp valve is

normally closed and said key is so constructed and related as to co-operate with a ring-like portion of a novel duplex valve forming a part of the adjacent C-natural valve, whereby to simultaneously seat said ring-like part when the D-sharp valve is opened in order to obtain the tone diminishing result described above.

A third distinction and improvement resides in the provision of an extra key operable by the third finger of the right hand for producing the tone F-sharp, the mechanism being such as to permit the production of a smooth trill or straight passage from F-natural to F-sharp, and the arrangement being such as to permit the old side mounted F-sharp trill key to be dispensed with entirely. As is known, practically all present day saxophones are provided near F-natural in the middle register with what is known as an F-sharp trill key, but in the present revision and improved arrangement such trill key and its valve is entirely dispensed with.

On present day saxophones middle B-flat is sometimes produced by sliding the tip of the index finger of the left hand from the B-natural key onto a small adjacent tab or B-flat key, and/or said B-flat tone is sometimes produced by depressing the B-natural key and simultaneously depressing F-natural key by the index finger of the right hand. This latter tone is however, frequently muffled, and therefore not consistent in quality with the B-flat tone produced by way of my improved side B-flat key arrangement to be later described in detail.

It follows that a fourth and important improvement is predicated upon the provision of a new remote control key operable by a finger of the right hand for producing a clean and undistorted passage between B and B-flat.

A fifth improvement is vested in the provision of new key between the customary high E-natural key and the new B-flat key to co-operate with the E-natural valve operating shaft, permitting a section of said shaft to oscillate in two directions, (instead of one direction as usual), and when oscillated in one of said directions to actuate the aforesaid ring-like member of the new duplex C-natural valve for decreasing momentarily the diameter of the C-natural vent, which said valve covers, in order to permit the playing of a trill between B and C-natural. By way of differentiation, I may add that this does away with the old side trill key between the tones B and C-natural and improves the quality of tone and facilitates fingerings.

In the drawings:

Figure 1 is a view in front elevation and section disclosing the principal features of the invention, the section being approximately on the line 1-1 of Figure 2.

Figure 2 is a side elevational view with portions of the mechanism omitted for clearness of observation and showing the D-natural valve, C-natural key, (low register), the control or key for high E-natural, the new B-flat key, and the duplex or sectional valve for making the B to C trill in middle register. 70

Figure 3 is a side view showing the new position of C-sharp valve in the lower register, and the usual operating keys for the tones G-sharp, C-sharp, B-natural and B-flat. 75

Figure 4 is a transverse section on the line 4-4 of Figure 3.

Figure 5 is an elevational view showing the new attachment for operating the D-sharp key in the upper register of the instrument to make for a trill between C-natural and D-natural. 80

Figure 6 is a fragmentary perspective view showing the operating rocker arm for controlling the D-natural and C-sharp valves in the lower register. 85

Figure 7 is a cross section on the line 7-7 of Figure 2 disclosing the aforesaid duplex or sectional valve. 90

Figure 8 is a view similar to Figure 7 showing the ring-like member of said valve seated.

Figure 9 is a view similar to Figure 7 disclosing the operating arms and mechanism more precisely. 95

Figure 10 is a rear face elevation showing how several old keys and valves are systematically omitted.

Figure 11 is a detail enlarged section on the line 11-11 of Figure 2. 100

Figure 12 is a diagrammatic isolated view showing the D-natural valve, C-sharp key, and operating connection between said valve and key.

Figure 13 is a similar detail view of the new trill attachment for optional use (C to D trill) with the ordinary D-sharp key in the upper register of the instrument. 105

Figure 14 is a detail view of the new F-sharp key and valve arrangement.

Figure 15 is a diagrammatic view of the new side control B-flat key and the associated valves and operating means therefor.

Figure 16 is a fragmentary longitudinal sectional view through the two master shafts seen on the right hand side of the instrument depicted in Figure 10, designed to show just how these shafts are constructed. 115

Figure 17 is a fragmentary perspective view detailing the essential parts of the mechanism utilized to produce either a trill or a regular alternating passage between the tones B and C-natural in either the middle or upper register as desired. 120

Figure 18 is an isolated perspective view showing the improved F-sharp key with parts in dotted lines to better bring out the operation of this particular improvement. 125

Figure 19 is a similar fragmentary perspective view designed to illustrate pictorially 130

the new remote control B-flat key and companion mechanism.

It is believed to be systematic to first describe the C-sharp valve and D-natural valve in the lower register of the instrument with the controls or operating mechanism for said valves.

In Figure 1 for example, the body or tubing of the instrument indicated at 16 is formed with the customary D-natural vent 17 and the corresponding pad or valve 18. This valve is carried by an actuating arm 19 formed integrally with an oscillatory rock-shaft 20 supported between the bearing posts 21 and 22, said shaft having an associated spring 23 for normally holding the D-natural valve 18 open.

This shaft 20 as seen better in Figure 4 is provided with a curvate operating finger or arm 24, which as also seen in Figure 6, is provided at its free end with a lug 25 which underlies the free end portion of a companion arm 26, the arm 26 being formed integrally on the long rockshaft 27 controlled by the customary C-sharp key 28 as seen in Figure 3. The aforesaid spring 23 (Figure 11) exerts spring pressure on these two arms 24 and 26 to normally lift the arm 26 and to maintain the C-sharp key 28 in its customary elevated position, as well as to hold the D-natural valve 18 normally open.

Thus, it is possible by depressing the key 28 (Figure 3) and rocking the shaft 27 to cause the arm 26 to press down on the lug 25, which in turn rocks the shaft 20 against the tension of the spring 23 to close the valve 18 by manual pressure. This C-sharp key 28 is an independent left hand (little finger) control for the valve 18, which valve by the way, serves to produce the tone C-sharp the tone being emitted through the C-sharp vent 29 in Figure 4.

The C-sharp valve is indicated by the numeral 30 and is carried on an arm 31, said arm being in turn rigid on the rocker or operating shaft 32 supported between bearings 33 and 34 on the left hand side of the instrument as shown in Figure 3.

The associate spring 35 anchored at one end on the post 33 serves to oscillate the shaft 32 in a direction to normally unseat or maintain the C-sharp valve 30 in an open position. This same shaft 32 is provided with an integral or rigid operating lever 36 which carries a finger piece 37 designated as the C-natural key. This lever 36 is located directly over the arm 24 and hence when the key 37 is depressed with the little finger of the right hand, said arm 24 is also depressed and the tension of both springs 23 and 35 is overcome so that both valves 18 and 30 are simultaneously closed for producing the tone C-natural.

Consequently, as before stated, it is possible to simultaneously close these two valves

18 and 30 to produce the tone C-natural with the little finger of the right hand or to individually close the valve 18 from the C-sharp key 28 to produce the tone C-sharp.

This same fundamental result was also obtained in the aforesaid pending application, but the operating mechanism herein illustrated is more simple and satisfactory and constitutes one of the features of the present invention to be hereinafter claimed. In this improved arrangement, it is to be noted that D-natural valve maintains its usual position, while the C-sharp valve has been shifted to the opposite side of the bell in order to simplify the action and better equalize the spring and valve arrangement.

I now call attention to Figure 5 showing the valve for producing the higher tones on the instrument, and it will be noted that 38 represents the usual lever actuated D-natural valve, 39 the D-sharp valve, and 40 the F-natural valve. In accordance with the present invention the D-sharp valve is slightly altered and is provided with an added extension or finger 41.

It is known, of course, that all three of these valves are normally spring-closed. In accordance with my idea, however, I provide a C and D-natural trill attachment controlled by the index finger of the left hand for opening this valve 39, said attachment including an extra key disposed in a longitudinal line with the customary bank of keys on the body of the instrument so that it is more easily accessible and readily operable when the instrument is in its proper attitude.

In accomplishing this result, I provide two additional bearing posts 42 and 43 with a rocker shaft mounted for oscillation therebetween, the shaft being indicated at 44 and provided with a key 45. This is to be hereinafter known as the new "C to D-natural trill key" and it is used for producing a rapid trill between C and D by depressing and holding the conventional C-natural key while alternately depressing and releasing the new D-natural trill key 45.

The shaft 44 is provided with a rigid lifting arm 44a which underlies the finger 41 so that by depressing the key 45, the valve 39 (ordinarily producing the tone D-sharp) can be opened. In Figure 1 it will be observed that the key 45 is so located as to simultaneously depress and close the underlying C-sharp valve 46. This valve 46 and its mechanism is of ordinary type and found on conventional saxophones. It is so mounted as to be closed simultaneously with the C-natural key operated by the second finger of the left hand.

In addition, the key 45 is so located that one edge portion thereof overlies the adjacent edge portion of the annulus or ring section 47 of a novel duplex valve (C-natural) indicated as a unit by the numeral 48. This

valve 48 is a new valve and serves several purposes. The closure section or pad of this particular valve 48 is distinguished by the numeral 49. The valve 48 is thus sectional and so constructed and arranged that by depressing the key 45 the ring 47 is simultaneously depressed against the adjacent C-natural vent 50, as seen in Figure 8, so as to make it possible to produce the improved C to D-natural trill perfectly in tune.

Under the present arrangement by simultaneously closing the valve 46 and seating the ring 47 the tone emitted through the usual D-sharp vent is lowered one-half tone in order to make the tone D-natural. Obviously then, the presence of this trill attachment makes it possible to produce a trill between the tone C-natural and D-natural by using the index and second fingers of the left hand in proper alternation.

To do this, it is necessary to hold the second finger of the left hand down against the C-natural key and to place the index finger of the same hand on the key 45 and to alternately raise and lower it. By so doing, the valve 39 is opened at the same time the ring 47 is seated, and by this action, as stated, lowers the pitch of the higher note one-half tone in order to produce the C to D-natural passage.

This attachment is an optional appliance, and has been found to operate satisfactorily for producing the aforesaid C to D-natural trill. Heretofore in order to obtain the same result, it was necessary to depress and hold down the C-natural key and to literally jump the hand back and forth in order to alternately depress and open the ordinary D-natural key. This was found to be awkward and the tone not sharply distinguishable because of the peculiar merging effect. Hence the provision of this novel attachment to better accomplish the result.

It will also be appreciated that C-natural valve 48 must be made up of independently operable sections in that it also constitutes the means for producing the tone B-natural when the valve, as a unit is closed. It is obvious then that the pad or valve section 49 not only functions as a valve but as a carrier for the B-natural key against which the index finger of the left hand is placed in making said tone B-natural.

In practice, this valve section 49 is provided with a suitable pearl button or finger piece as is shown for convenience of operation.

I call attention at this time to Figure 1 wherein the numeral 51 designates the side located E-natural key for controlling the E-natural valve 53 in the upper register. This is carried by the new two-part spring-pressed rockershaft 52 mounted for oscillation in suitable bearings, and in order to unseat the E-natural valve 53 it is necessary to press

down on this key 51 in the ordinary manner.

The shaft 52 as before indicated is made up of two parts or sections which are simultaneously oscillated when operated in one direction and separably operable when oscillated in the opposite or reverse direction. The lower section is distinguished by the numeral 52a (see Figure 17) and this has an arm 51a at the lower end carrying the key 51 (not shown). Then as seen in Figure 11, the free end portion 56 of an auxiliary key 55 is engageable beneath this arm for rocking the shaft section 52a in a direction from left to right in Figure 17.

There is a rigid bell-crank finger 52b on the upper end of the shaft section 52a which cooperates with an adjacent rocker arm 53b carried by the short shaft section 53a and since the latter section 53a carries the E-natural valve 53 it is evident that when the key 51 is depressed, this rocks the shaft 52 as a unit through the medium of the parts 52b and 53b to lift the E-natural valve 53.

The shaft section 52a also has a peculiarly or suitably shaped presser finger 54 whose terminal is located to engage and depress the ring 47. The ring 47 is formed integrally with a lifting finger 47b on the sleeve section 47a of an adjacent shaft 62. In fact, the finger 47b is engageable beneath the complementary operating member 46a for the C-sharp valve 46.

It is evident therefore that by depressing the E-natural key 51 in the usual direction from right to left in Figure 17 both shaft sections 52a and 53a are oscillated as a unit to raise the E-natural valve. Secondly, by depressing the C-natural side key 55 the shaft section 52 alone is oscillated in an opposite direction, that is from left to right in Figure 17.

In so doing the finger 54 depresses and seats the ring 47. In addition, this rocks the sleeve 47a and complementary finger 47b which in turn actuates the member 46a to simultaneously close the valve 46. The result is that the diameter of the C-natural vent is at this moment decreased and the tone emanating therefrom is C-natural.

By holding down the key 55 and its ring 47 and alternately raising and lowering the valve 49 the passage produced is from B to C as is obvious. It is evident of course that when the valve 49 is seated on the ring 47 the tone is emitted through the B-natural vent. A close observation of Figure 17 will serve to clarify this new action.

It is evident that in making the tone B-natural in the middle register it is necessary to depress the double valve 48 as a unit. This is done by placing the index finger of the left hand on the valve closure 49 and employing it as a key for the purpose. In accordance with the improved arrangement for produc-

ing the tone B-flat, it is necessary, of course, to depress the next lower valve 58.

Sometimes, this is done by sliding the same index finger down to reach and depress the usual small key 59. This is an objectionable type of fingering, and I therefore provide a remote control for the valve 58. This is in the nature of an additional or new B-flat key designated by the numeral 60.

10 As seen in Figure 15 and in Figure 19, it is carried by an arm 61 operatively connected by way of a short rocker arm 62a (a new part) with the main unit of the rocker shaft 62 which has an operating connection at 63 with this valve 58. This provides a smooth trill between B-natural and B-flat and permits B-flat to be controlled at a remote point by the index finger of the right hand instead of attempting to bridge the gap between the keys 59 and 49 with the index finger of the left hand as would ordinarily be necessary. This is one of the most simple improvements 20 of the invention constituting the novelty of this application.

25 In order to produce a B to B-flat trill simply depress and hold B-natural and alternately raise and lower the key 60 to operate valve 58.

The next improvement is the control for 30 F-sharp mounted on the body of the instrument in line with the ordinary or master bank of keys. As before stated, F-sharp is produced on the ordinary saxophone in several different ways, and generally when 35 rapid manipulation is necessary or a trill necessary, a side trill key (not shown in this case) is provided. In fact, in accordance with the present invention the usual trill key is dispensed with entirely, and what I do is to 40 provide a lever 64 having an F-sharp key 65, said lever being formed as an integral part of a rocker shaft 66 carrying the valve 67 (see Figure 14) utilized when properly operated to produce the tone F-sharp.

45 It is to be remembered as seen in Figure 1 that F-natural is produced by the key 68 and E-natural by the key 69. Likewise, D is produced by the key 70 when all three fingers of the left hand are down. The presence of this 50 new key 65 between the keys 69 and 70 (see Figure 18 in particular) places it in a position for convenient manipulation by the third finger of the right hand.

In descending the chromatic scale, such as 55 for example, B, A, G-sharp, G-natural, in the usual way with the left hand, it is necessary, in order to produce F-sharp to depress the key 65 with the third finger of the right hand. This seats the G-natural valve 67 as 60 seen in Figure 18, producing the tone F-sharp. In making a trill from F-natural to F-sharp, simply depress the key 65 and hold it down while alternately raising and lowering the key 68.

65 In order to appreciate some of the surpass-

ing merits of the refinements of my improved instrument it is really necessary for the reader to be familiar with the standard or conventional marketed saxophone. Taking the ordinary saxophone in hand it will be observed that the main bank of keys and fundamental or master row of pads or valves is on the front face of the tubing of the instrument while in normal playing position.

70 Next, it will be noted that there is a cluster of three keys (D and F-natural and D-sharp) on the left side near the mouthpiece of the instrument. My improved C to D attachment is associated with the usual D-sharp key. Otherwise, this trio of keys is unchanged. The operating key 45 of said attachment is located over the high C-sharp valve near the B-natural key and is therefore in proper line with the main bank of keys.

Near F-natural (middle register) and to 75 the right of the said main row of keys is a single lever valve and corresponding vent known as an F-sharp trill key for optional use. Further to the right of this and in line with the high E-natural key are two keys 80 frequently referred to as side trill keys but sometimes used in ordinary execution.

85 One of these is a B-flat key and the other used in making one of the tones of a passage involving B-natural to C-natural (generally a trill). Needless to say, these side keys are awkwardly misplaced and therefore difficult of rapid execution. Therefore, I have closed all three of these vents, dispensed with the valves, levers, shafting etc. In fact, I put my 90 new F-sharp key right in line with the main bank, provide a simple duplex valve for making the tones B to C-natural having the additional function of making a rapid passage from C to D-natural, and simplifying 95 the operation of B-flat.

100 Particularly do I emphasize the use of the duplex valve which co-operates with the C-natural vent, for when the valve, as a unit, is closed its presence is not noticed, but when the ring is seated the tone is reduced somewhat, whereby to enable the playing of D to C-natural, etc.

110 Summarizing the revelations of the invention, five factors are to be remembered. First, the unnecessary jumping and shifting of hands is overcome by the new C-natural and C-sharp arrangement in the low register. Secondly, the new F-sharp key (middle register) is introduced as an easily playable 115 means directly in line with the main bank of keys, this being readily operable by the third finger of the right hand.

120 Third, the high D-sharp attachment is incorporated in such a manner and position as to permit speedy playing of the tones D-natural to C-natural using the index and second fingers of the left hand. Incidentally, 125 these tones cannot be rapidly executed on 130

present day saxophones because the hand has to be "jumped" bodily back and forth.

Fourth, I recall the systematically arranged method and remote control means of making the tones B to B-flat in the middle register.

And fifth, the useful duplex valve and operating means for half tone diminishing to allow playing of B-natural to C-natural in tune and with dependable skill.

I claim:

1. A saxophone comprising a tubular body including a conventional bell, the bend of the bell being formed on one side with a D-natural vent and a corresponding valve, the tubing being formed on the opposite side with a C-sharp vent and a corresponding valve, a longitudinally elongated rockably mounted shaft on the tubing provided at its upper end with a C-sharp key, an independent operating connection between the lower end of said shaft and said D-natural valve, said operating connection serving to normally unseat said D-natural valve, a second oscillatory shaft mounted for operation within the vicinity of the bend of said bell, said C-sharp valve being rigidly supported thereon, a spring operating on said second-named shaft for normally urging said C-sharp valve to open position, a C-natural key carried by said second shaft, said C-natural key being operatively associated with the operating connection for said D-natural valve whereby upon depressing said C-natural key both of said valves will be closed, or by depressing said C-sharp key, the D-natural valve alone will be closed.

2. A saxophone comprising a tubular body including a conventional bell, the bend of said bell being formed at one side with a D-natural vent, a pair of spaced bearing posts on said body, a shaft mounted for oscillation between said posts, a laterally directed finger carried by the intermediate portion of said shaft and terminating in a lug, a spring anchored on one of said posts, and connected at its free end with said shaft, a rigid arm on said shaft, a D-natural valve carried by said arm and co-operable with said D-natural vent, and an elongated shaft mounted on an opposite side of the tubular body for limited oscillation and formed at its upper end with a C-sharp key and provided at its lower end with a laterally directed curved arm whose free end portion is engageable with said lug, said tubing being further provided on a side opposite to said D-natural vent with a C-sharp vent, a third shaft mounted for oscillation on the tubing within the vicinity of said vent, a rigid arm carried by said last-named shaft, a C-sharp valve on said arm co-operable with said C-sharp vent, a spring for normally opening said C-sharp valve, a lever arm carried by said third shaft and terminating in a C-natural key, said lever over-

lying and bearing upon the adjacent operating finger, whereby when said C-natural key is depressed, both valves will be simultaneously closed and when said C-sharp key is depressed, the D-natural valve alone will be closed.

3. In a saxophone, a tubular body terminating in a bell and provided adjacent said bell with a D-natural vent on one side of the bell and a C-sharp vent on the opposite side of the bell, a D-natural valve for closing said D-natural vent, a C-sharp valve for closing said C-sharp vent, both of said valves being normally unseated, finger actuated means operable by the little finger of the right hand for simultaneously seating said valves and closing said vents, independent finger actuated means for the left hand for separately closing said D-natural valve, and multiple spring means for automatically unseating said valves and permitting the desired single and double action of said valves.

4. A saxophone comprising a tubular body formed near its upper end with a C-sharp vent, an adjacent C-natural vent, a B-natural vent, and a D-sharp vent, a normally spring-closed D-sharp valve for said D-sharp vent, three independent normally open valves for closing the B-natural, C-natural and C-sharp vents, said C-natural valve being composed of two sections, the lower section being a ring, and the outer section a pad for closing said ring, said sections being independently operable, a C to D-natural trill attachment mounted on said tubing and operatively connected at one end with said D-sharp valve for lifting it to open position, and formed at its opposite end with a D-natural trill key overlying said C-sharp valve and independently engageable with the ring section of said sectional valve, whereby upon closing the C-natural valve with the second finger of the left hand and depressing said D-natural trill key, said ring section is seated to diminish the pitch of the D-sharp tone one-half tone and to permit the playing of a C-natural to D-natural trill.

5. A saxophone comprising a tubular body provided on its upper portion with a high D-sharp vent, a spring-closed D-sharp valve co-operable with said vent and formed with a marginal extension, a pair of supplementary bearing posts on the tubing near said valve, a rock-shaft mounted for oscillation between said bearing posts and provided at its upper end with a lifting finger underlying said extension, said shaft being formed at its opposite end with a D-natural trill key operable by the little finger of the left hand, a C-sharp vent underlying said trill key, a C-sharp valve co-operable with said vent, a C-natural vent adjacent to said C-sharp vent, a duplex C-natural valve co-operable with the C-natural vent and including an inner ring section and an outer pad section for

5 closing the ring section, said D-natural trill key being engageable with the adjacent portion of the ring section independent of the pad section whereby when said trill key is depressed and said ring section seated on the C-natural vent, the consequent tone being that of D-natural.

10 6. A C-natural to D-natural trill attachment for a saxophone comprising a pair of auxiliary bearing posts, a rocker shaft mounted for oscillation between said posts, a curvate lifting arm on one end of the shaft having its free end adapted to engage and unseat a conventional D-sharp valve, said shaft being provided at its opposite end with an integral arm carrying a trill key, and an associated duplex valve for co-operation with said trill key, comprising an inner ring adapted for co-operation with a C-natural vent, and an outer pad for closing said ring, said pad having the additional function of carrying a B-natural key, and said ring co-operating with said C-natural vent in diminishing the pitch of the tone, the trill key being co-operable with the ring section for momentarily seating it.

15 7. A saxophone comprising a tubular body formed adjacent its lower portion with longitudinally aligned vents for producing the tones G-natural, F-sharp, F-natural and E-natural, a plurality of corresponding valves for said vents, said F-sharp valve being provided with an F-natural key, said F-natural valve being provided with an E-natural key, said E-natural valve being provided with an E-natural key, an F-sharp key located between the E and D keys and operatively connected with said G-natural valve for independently closing said valve at leisure to produce the tone F-sharp when the F-sharp valve is opened, or to produce an F-natural to F-sharp trill when the corresponding keys are operated in proper succession.

20 8. A saxophone comprising a tubular body formed adjacent its lower portion with longitudinally aligned vents for producing the tones G-natural, F-sharp, F-natural and E-natural, a plurality of corresponding valves for said vents, said F-sharp valve being provided with an F-natural key, said F-natural valve being provided with an E-natural key, said E-natural valve being provided with a D-natural key, an F-sharp key located between the E and D keys and operatively connected with said G-natural valve for independently closing said valves at leisure to produce the tone F-sharp when the F-sharp valve is opened, or to produce an F-natural to F-sharp trill when the corresponding keys are operated in proper succession, all of said keys being arranged in substantial longitudinal alinement in the standard key bank so as to permit the additional F-sharp key to be conveniently manipulated with the third finger of the right hand.

25 9. A saxophone comprising a tubular body provided with longitudinally spaced vents, a normally open finger closed valve co-operable with one of said vents for producing the tone B-natural, said valve being provided with a B-natural key, and adjacent independently operable valve for closing the next adjacent vent for producing B-flat, a rockshaft mounted on the body and operably connected with said second-named valve, said rocker shaft being provided at its lower end with a B-flat key adapted to be manipulated by a finger of the right hand, whereby to provide a side remote control for said second-named valve to permit a B-natural to B-flat trill.

30 10. A saxophone comprising a tubular body provided adjacent its upper portion with a plurality of longitudinally spaced vents for producing the tones B-natural and B-flat in the middle register, a valve provided with a B-natural key for covering one of said vents to produce the tone B-natural, a second valve for covering the adjacent vent to produce the tone B-flat, a pair of longitudinally spaced bearing posts on the tubular body, a rock-shaft mounted between said posts, said rock-shaft being provided at its upper end with an arm rigidly connected to said B-flat valve, and a B-flat key for operating said shaft, said B-flat key being located on the right hand side of the intermediate portion of the body of the instrument to be controlled by the right hand, so as to provide a remote trill key permitting a trill from B-natural to B-flat by depressing and holding the B-natural key and alternately raising and lowering said B-flat key.

35 11. A saxophone comprising a tubular body provided on its upper portion with an E-natural vent, an E-natural valve for closing said vent, a two-part rocker shaft mounted in bearings on said body, said E-natural valve being operatively connected with the upper part of said shaft, an E-natural key on the lower end of said shaft for operating said E-natural valve, the lower section of said shaft being rotatable in unison with the upper section when the E-natural key is depressed, a pivotally mounted C to B-natural trill key mounted within the vicinity of said E-natural key and operatively connected with the lower section of said shaft for rotating said lower section in a direction opposite to its normal direction of rotation, said tubular body being provided on its upper portion with three vents, a pair of valves co-operable with said vents, a third valve co-operable with the remaining vent, and an associated C-natural key co-operable with said third valve, the intermediate valve being a duplex valve and including an inner ring co-operable with the underlying vent, and an outer pad, the last-named section of said shaft being provided with a presser finger co-operable with said ring to seat the ring.

to decrease the size of the port of said vent, whereby by depressing and holding said ring down and alternately raising and lowering said outer pad, it is possible to produce a trill from B-natural to C-natural.

- 5 12. A saxophone comprising a tubular body provided with a pair of longitudinally spaced ports, a valve for closing the lowermost port, a C-natural key associated with 10 said valve for depressing it, a duplex valve associated with the uppermost vent, said duplex valve including an inner ring for diminishing the orifice of said vent, and a pad for closing said ring, an adjacent presser finger for seating said ring against its vent, and a remote control key operable by the 15 right hand for seating and unseating the ring, whereby by holding said C-natural key down and alternating the open and closed position 20 of said pad, it is possible to produce a trill between C-natural and B-natural.

13. In a saxophone of the class described, a tubular body provided on its upper portion with an E-natural vent and further provided 25 on its frontal portion below said vent with a C-sharp vent, a C-natural vent, and a B-natural vent, a pair of longitudinally spaced bearing posts on said body, a rocker shaft mounted between said posts, and including 30 an upper section provided with a rigidly mounted E-natural valve for closing said E-natural vent and a rocker arm, a lower shaft section provided at its lower end with a rigid E-natural key and formed at its upper end 35 with a substantially L-shaped finger for engaging and operating said rocker arm when said E-natural key is depressed, a pivotally mounted C-natural trill key on said body engageable with said lower shaft section for 40 oscillating it independently in a direction opposite to said upper shaft section, a C-sharp valve for closing said C-sharp vent, an operating member rockably supported from said body, a ring co-operable with said C-natural 45 vent for temporarily and proportionately reducing the orifice thereof, an independently operable closure for said ring-like member, said ring-like member having operating connection with the C-sharp valve, a presser finger carried by the lower shaft section and engageable with said ring-like member, whereby when said C-natural trill key is depressed, said lower shaft section is oscillated 50 in a direction to simultaneously seat the ring-like member and close the C-sharp vent to produce the tone C-natural through the opening of said ring-like member, and whereby when said closure is operated against the ring-like member an alternating passage be- 55 tween C-natural and B-natural is playable.

60 14. In a saxophone, a tubular body provided with a C-sharp vent, a B-natural vent, and an intervening C-natural vent, a ring closure co-operable with said C-natural vent, 65 an independently operable valve co-oper-

able with said ring closure, a remote control for said ring member including a C-natural trill key, an operating connection between the ring member and C-sharp valve for closing said valve when said ring member is seated, whereby upon holding the C-natural trill key down and alternately raising and lowering the ring valve, it is possible to produce a passage from B to C.

70 In testimony whereof I affix my signature. 75
FULVIO CALVANI.
